DESIGN FOR A BLOWPIPE

Laurence Oliphant, Maplewood, N. J., assignor
to Oxweld Acetylene Company, a corporation
of West Virginia

Application November 19, 1930, Serial No. 37,720

Term of patent 14 years

To all whom it may concern:

Be it known that I, LAURENCE OLIPHANT, a citizen of the United States, residing at Maplewood, in the county of Essex and State of New Jersey, have invented a new, original, and ornamental Design for a Blowpipe, of which the following is a specification, reference being had to the accompanying drawing, forming part thereof.

The dominant feature of my design resides in the handle configuration.

Figure 1 is a perspective view of a blowpipe, showing my new design in full lines.

Figure 2 is a profile of the outer periphery of the handle portion of Figure 1.

I claim:

The ornamental design for a blowpipe substantially as shown and described.

LAURENCE OLIPHANT.
